UNITED STATES PATENT OFFICE.

LUDWIG MALZ, OF NEW YORK, N. Y., ASSIGNOR, BY MESNE ASSIGNMENTS, TO WALLACE ADDRESSING MACHINE COMPANY, INC., A CORPORATION OF NEW YORK.

PLATEN ATTACHMENT FOR STENCILING TYPE-WRITERS.

1,172,896.

Specification of Letters Patent.

Patented Feb. 22, 1916.

Application filed June 9, 1909. Serial No. 501,107.

To all whom it may concern:

Be it known that I, LUDWIG MALZ, a citizen of the Empire of Germany, residing in New York, in the borough of Manhattan, 5 county and State of New York, have invented certain new and useful Improvements in Platen Attachments for Stenciling Type-Writers, of which the following is a specification.

10 This invention relates to platen attachments for stenciling type-writers, and has for its object to provide means whereby address stencils may be pricked in a flat state, so as not to require their bending as heretofore, which bending oftentimes injured their frame, so as to make their further manipulation in the addressing machines impracticable and sometimes impossible.

15 For this purpose my invention consists 20 of a flat stencil blank holder; and the invention consists further of a platen attachment for stenciling typewriters, comprising a holder for the stencil blank, means for placing said holder in position to receive 25 the blank in a flat condition, and means for placing said holder in proper position to enable the blank to be impressed, while in flat condition; and the invention consists lastly of certain novel features and combination of parts, such as will be described 30 hereinafter and finally pointed out in the claims.

35 Referring to the drawings, Figure 1 is a plan view of a well-known type-writer carriage with my improved attachment secured thereto, Fig. 2 is a sectional longitudinal section of my attachment taken on line 2—2 of Fig. 1, and drawn on a larger scale, showing also an address-stencil supported 40 thereon, Fig. 3 is a vertical transverse section taken on line 3—3 of Fig. 1; Fig. 4 is a vertical transverse section taken on line 4—4 of Fig. 1, and Fig. 5 is a vertical transverse section taken on line 5—5 of Fig. 1.

45 Similar characters of reference indicate corresponding parts.

Referring to the drawings, and more particularly to Fig. 1, the usual typewriter carriage 10 has guide-wheels 11 and 12, as 50 well as a shifting-handle 13, and the platen 14 with platen-shaft 15 having an operating handle 16, all as well known. The spacing-handle 17, pawls 18 and 19, with spring 20, and ratchet 21, as also the spring-actuated 55 check-roller 22, are also well known, and

need no further description. The platen 14 is provided with a layer 51 of soft material, as cloth, felt, rubber, etc., which layer is held in place by a clamp and thumb-screw 71. This also was well known in stenciling 33 typewriters. Heretofore, however, it was usual to clamp a stencil-blank to and around the cylindrical platen of a typewriter, and then cause it to be stenciled by the operation of the typewriter keys. A 65 stencil-blank is shown in cross-section in Fig. 2, by 25, and consists as is well known of paper, surrounded by a frame 26 of cardboard, or similar material, which blank after being stenciled is used in the addressing machines. By the bending of these frames on the usual cylindrical platen, the frames would be caused to become cracked, and so injured, that their further use in the addressing machines is impaired. Furthermore, in case the operator made an error in 70 the stenciling and desired to correct it by impressing a new character over the erroneously placed one, it was almost impossible, except in very few exceptional cases, and 75 then only after painstaking efforts, to impress the correct character exactly over the erroneous one. Some efforts to obviate these disadvantages have been made but these have failed, since they were cumbersome and 80 expensive, and did not accomplish that for 85 which they were intended.

To provide a machine wherein both the accuracy and speed of operation may be increased, I provide a sliding flat holder 30, 90 having side-guides 31, front-guides 32 and rear-guides 33, which surround a stencil blank when placed in position and hold it securely in place against shifting. This holder 30 has racks 34, engaged by gear-wheels 35 secured to the ends of the usual platen 14 and is provided at its front with a recessed portion 36, to enable the blanks to be readily placed in position and removed therefrom. Side-parts 37 extend upwardly 100 from the holder 30 which engage guide-ways 38, suitably secured to the carriage 10. The platen-shaft 15 is provided with a collar 40, provided with figures 1 to 5 on its periphery, which is held in position by a 105 smaller collar 42 adjustably by a screw 43. An index-plate 41 is supported by the carriage and serves to point to the figures on the collar by covering the remaining figures, the figures being so arranged as to corre- 110

spond to the relative positions of the holder 30, and the object of the same is to determine which part of the blank is being stenciled. When the holder 30 with its blank is 5 in a position corresponding to the stenciling of the first line on the blank, the figure 1 would appear and the remaining figures be hid by the index-plate 41. When this line is 10 finished and the spacing mechanism operated by the handle 17, the platen is rotated and the holder with its blank brought in a position corresponding to Fig. 2, and so on. After the last line is stenciled, the holder 30 is returned to its initial position by one 15 movement of the handle 45 secured to the platen-shaft 15. The stenciled blank is then, by gripping it, which is permissible by means of the recess 36, removed from the holder.

20 The outward position of the holder with its blank is shown clearly in Fig. 3, and a position ready for stenciling is shown in Fig. 4, the typewriter bar 46 with stencil-type 47 being shown in dotted lines, while an end 25 view of the collar 40 with its figures is shown in Fig. 5. In case a correction is necessary it may be readily made by simply returning the blank to the required line, being guided thereby by the figures on the 30 collar and by reason of the flat condition of the blank and its being fitted in the holder, the identical place may be reestablished and the correct impress made.

35 By my improvements, which are simple and efficient, the output for stenciling typewriters is greatly increased, the blanks with their frames remain in substantially the same original and unimpaired condition,

thereby are very efficient in their later use in the addressing machines, and also corrections, if any, may be readily made, which is 40 a great advantage in the practical operation of the machines.

I have shown one embodiment of my invention, but I do not wish to be limited to 45 the details thereof, since changes may be made without departing from the spirit of the same.

Having thus described my invention, I claim as new and desire to secure by Letters Patent:

In an attachment for a typewriting machine having a rotatable cylindrical platen, a movable blank holder adapted to move into or from the space under the platen, 55 gear-wheels at the ends of the platen, a movable blank-holding frame having at its ends racks adapted to be engaged by said gear-wheels whereby when said platen is rotated said frame is moved from under the platen, 60 said platen being adapted to engage a blank in the blank-holding frame when the blank is being actuated, said holder-frame comprising a flat bottom part upon which the blank may rest and upstanding flanges 65 forming side, front and rear guides for the blank, the front part of said holder being provided with a recess for permitting the blank to be engaged by the fingers.

In testimony, that I claim the foregoing 70 as my invention, I have signed my name in presence of two subscribing witnesses.

LUDWIG MALZ.
